UNITED STATES PATENT OFFICE.

CHARLES V. WRIGHT, OF TAMAQUA, PENNSYLVANIA.

INTERNAL-COMBUSTION ENGINE.

Application filed November 10, 1925. Serial No. 68,186.

The object of my invention is to provide improvements in pistons for internal combustion engines which will have all or any of the advantages hereinafter set forth in regard to construction and action, and with this end in view my invention consists in whatever is described by or is included within the terms or scope of the appended claims.

In the drawings:

10 Fig. 1 is a vertical section of a piston embodying my invention;

Fig. 2 is a perspective view showing the trunk and head parts separated.

An important feature of my invention is 15 a piston of sections that include an interchangeable head, so that by interchanging heads of different sizes, the compression may be increased or diminished, and thus the horse-power changed with no change of piston stroke or displacement or diameter of bore.

The piston shown in the drawings as one embodiment of my invention comprises a trunk, or lower part, 10, having the wrist pin, 11, with which the connecting rod is connected, and a removable head or cap part, 12, the abutting faces of the two parts being flat or plane, so they may slip or slide laterally upon one another before they are 25 secured together by the fastening bolts, 13, which pass each through a hole, 14, in the head section and an alining hole, 15, in the trunk section and screw into a threaded hole in the wrist pin bushing, 16, preferably of 30 brass. I thus make the bushing serve as a nut, because should the thread strip, the bushing may be removed and another substituted, whereas if the thread were in the trunk, the whole trunk would have to be 35 thrown away to supply a new, threaded hole for the bolt.

The head of the bolt is on the outside of the piston head section, so that it is of convenient access for turning the bolt, in assembling or taking the piston apart. The two bolts are eccentric to the piston, and hence, in turning the bolts, there is no tendency to rotate the piston which might result in some twisting of the rod connection 45 with the wrist pin and cause serious non-alignment of parts.

To secure lightness, the head section is chambered on its side next to the trunk, but the bolt hole, 14, is formed in a thick lug, 17, 50 so that there is no danger of any breakage of the head section at the bolt holes which

would result in loose fragments of the piston that would score or cut the cylinder walls.

The bolt holes, 14, are not a close or sliding fit with the bolts, but are substantially larger in diameter, so that besides making easy the insertion of the bolts, some side play of the piston sections is possible which is important in that the section parts can thereby adjust themselves to the cylinder, when assembling the engine. This looseness is also an advantage because when the bolts are unscrewed from the bushings, and the portions of the bolts that stick above the head section are grasped between the fingers and thumb the bolts will bind enough in the holes to enable them to be used as a handle to lift the head section out of the engine cylinder.

While any desired bolt lock may be used 75 for the bolts, 13, their separated arrangement enables a very simple lock to be used that consists merely of a metal strip, 18, with holes near each end for the passage of the bolts, and capable of being bent up alongside each bolt head and in contact therewith to form the lock. When the bolts are to be removed the head-engaging portions of the strip are bent out of contact therewith. The lock so formed has no small parts apt to be 80 heated so as to cause ignition of an engine charge after the spark has been cut off.

The head section has annular grooves for split packing rings, 19, and these being carried by the head are removed and replaced 85 with it from and to the cylinder. The end portion of the trunk, 10, adjacent the head, has an annular groove, 20, that cuts across the upper portion of the wrist pin bushings and the wrist pin, and thereby is provided packing ring space, for preferably two split packing rings, 21 and 22, placed one above the other, and confined in such space by the overlapping end of the head section. These packing rings thus hold the wrist pin from 90 endwise motion, so that no screw or pin for that purpose is necessary and, hence, the wrist pin being free to turn in the trunk, and the connecting rod being free to turn upon the wrist pin, there is possibility of 95 self adjustment or compensation for non-alignment, or non-parallelism of parts which obviate serious strains that would be set up were the wrist pin fixed by a pin at any one of the three points mentioned.

It will be observed that the packing rings, 21 and 22, where they cross the wrist pin

ends, the bushing and the portion of the piston section adjacent the bushing, have bearing contact with the surfaces which they cross and thus though the packing rings cross 5 the hole in the piston provided for the wrist pin and the bushing, nevertheless, a gas-tight joint between piston and cylinder wall is preserved, so that no loss of compression can occur, nor can there be any passing of oil 10 by such packing rings.

Should it be desired, however, the wrist pin can be engaged by the inner ends of the bolts, 13, but this would lose the advantage of the wrist pin free to rotate, and 15 would require nice work to secure clamping contact of the bolt heads or the piston head section.

The packing rings, 21 and 22, though serving to hold the wrist pin from endwise motion, are so situated that they perfectly seal 20 against the passage of oil to the combustion chamber, and any surplus oil is scraped off by the edge of the lower ring and may freely pass into the open end of the bushing and 25 work its way along the wrist pin and to the threaded hole in the bushing and so prevent the bolt therein from becoming fast and troublesome or impossible of removal.

The two split packing rings 21 and 22, 30 are arranged to break joints to make a perfect seal.

The removal of the packing rings, 21 and 22, is very simple. With the engine head removed, and with the piston at compression 35 stroke, the head section with its packing rings, is removed. This uncovers or frees the packing rings, 21 and 22, which acting expansively will bear against the cylinder walls. The crank shaft now being turned 40 to retract the piston trunk, the rings, adhering or sticking to the cylinder walls will be left behind, and can easily be picked out by hand. In this connection I note an important advantage. The workman has access 45 to the cylinder from the top, for fitting the rings, and the portion of the cylinder exposed is that where the rings work, and not some other portion, as when access is had from the bottom of the cylinder, and where the mechanic is on his back and at a disadvantage in his work for that reason, and nobody can see what he is doing and whether 50 his work is done right.

An aluminum piston desired because of the 55 lightness of aluminum, is impractical because the harder metal packing rings cut or wear the top walls of the ring grooves from the pressure of the top walls against the

rings, under the pressure of the explosion. But I can make the trunk section, which is the greatly larger part of the piston, of the light aluminum, because I make the head section of cast iron which has all the packing ring contacts that must stand the wear.

What I claim is:

1. A piston for internal combustion engines having a wrist pin, a ring encircling the piston that crosses the wrist pin ends, a bushing in the piston at each end of the wrist pin, a connecting rod free on the wrist pin between the bushings, the wrist pin being free to turn in the bushings, a separable head section for the piston, and bolts extending through such head section and engaging threaded holes in said bushings, lubricating oil having access to the portions of the bolts in the bushings.

2. A piston for internal combustion engines having a wrist pin, a ring encircling the piston that crosses the wrist pin ends, a bushing in the piston at each end of the wrist pin, and a connecting rod free on the wrist pin between the bushings, the wrist pin being free to turn in the bushings, a separable head section for the piston, and bolts extending through such head section and engaging threaded holes in said bushings.

3. A piston for internal combustion engines having a wrist pin, a packing ring encircling the piston that crosses the wrist pin 90 ends, the end surface of the ring opposite the end of the piston in the combustion chamber being exposed in a space for oil in the piston side at the wrist pin end, the piston having adjacent the wrist pin ends a surface with which the interior of the ring contacts adjacent such ends, said packing ring on its inside having packing contact throughout its circumferential extent with the piston surface, and a connecting rod on 95 the wrist pin.

4. A piston for internal combustion engines having a wrist pin, a packing ring encircling the piston that crosses the wrist pin ends, the pin being free to turn on its axis, 100 the piston having adjacent the wrist pin ends a surface with which the interior of the ring contacts adjacent such ends, said packing ring on its inside having packing contact throughout its circumferential extent with the piston surface, and a connecting rod on the wrist pin.

In testimony whereof I hereunto affix my signature.

CHARLES V. WRIGHT.
